United States Patent Office

Des. 183,369

Patented Aug. 12, 1958

183,369

THERMOSTAT

William A. Ray, North Hollywood, and Mario D. Rosiello, Glendora, Calif., assignors to General Controls Co., Glendale, Calif., a corporation of California

Application September 23, 1957, Serial No. 47,808

Term of patent 14 years

(Cl. D52—7)

Figure 1 is a front view of a thermostat embodying our new design.

Figure 2 is a top plan view thereof.

Figure 3 is a side elevational view thereof.

The faceted portions shown in full lines are repeated throughout the circular center area as indicated by the broken lines in said area.

The numerals shown in broken lines on the dial face in Figure 1 are for illustrative purposes only.

We claim:

The ornamental design for a thermostat, substantially as shown and described.
